[57] CLAIM

The ornamental design for a two-tiered table, as shown
and described.

DESCRIPTION

FIG. 1 is a front perspective view of a two-tiered table
showing my new design;

FIG. 2 is a side perspective view thereof, the opposite
side view being a mirror image of that shown; and

FIG. 3 is a bottom perspective view thereof.

*FIG. 1**FIG. 2**FIG. 3*
